CURRENT CONTROLLING DEVICE

John M. Heddaeus, Detroit, Mich., assignor, by
mesne assignments, to Edward S. Evans, De-
troit, Mich.

Application February 20, 1939, Serial No. 257,487

13 Claims. (Cl. 200—113)

The present invention relates to means for rapidly and recurrently increasing and decreasing the flow of electrical current in a circuit, and, in the herein disclosed embodiments, is particularly directed to improvements upon the structures disclosed in Schimkus application Serial No. 179,893, filed December 15, 1937, now Patent No. 2,163,709, granted June 27, 1939, and in its parent Schimkus and Dumke application, Serial No. 4,056, filed January 30, 1935, now Patent No. 2,163,708, granted June 27, 1939.

Generally speaking, the above identified applications disclose a device wherein a column of mercury of substantially greater length than width is subjected to the flow of an electrical current, the cross-sectional area of the column being so proportioned relative to the amount of electrical energy which is transmitted through the device, that the current causes a part of the mercury in the column to be converted from the liquid phase, in which it is a relatively good conductor, to a vapor phase, in which it is a relatively poor conductor. The conversion, by increasing the resistance current flow through the device either interrupts or so far reduces the flow of current, and consequently the heating action, that all or part of the vaporized mercury recondenses into the liquid phase, thereby either partially or entirely restoring the original conductivity of the column. The partial or entire recondensation of mercury causes an increase in or resumption of the current flow, thus again causing the above mentioned conversion to the vapor phase. The device is thus effective to translate the output of a direct current source, such as a battery, into a pulsating current, having current variations of substantially uniform magnitude and frequency.

The present invention is directed to improvements upon the above structures, whereby the magnitude as well as the frequency of the pulsations may be made more uniform, whereby the resultant pulsating wave form may be improved, and whereby the efficiency and general operating characteristics of the device may be improved.

With the foregoing considerations in view, principal objects of the present invention are to provide a device of the above generally indicated character, which is simple in construction, which may be manufactured and assembled extremely economically, and which is reliable and efficient in operation; to provide such a device characterized as embodying a column of material having the property of changing, in response to increases and decreases in applied heat, between conditions

in which it is a relatively good and a relatively poor conductor, characterized in that the point in the material at which the transition occurs, is confined and controlled; to provide such a device in which transition involves changing between liquid and vapor phases, and in which the point at which the transition occurs is closely confined and controlled; to provide such a device wherein the column is of substantially greater length than diameter, but wherein the current is required to pass through only a relatively short portion of the column; to provide such a device comprising generally a pair of conducting members separated by an insulating section, wherein a thin, relatively fine column of the material extends throughout the members, the arrangement being such that the transition of the material occurs in the relatively short insulating section; to provide such a device wherein the opposite ends of the loading column are subjected to relatively high pressures, so as to assist in the recondensation of material from the vapor to the liquid phase; and to provide such devices embodying improved structural relationships of the parts, whereby the manufacture and assembly thereof is facilitated.

With the above as well as other objects in view, which appear in the following description and in the appended claims, preferred but illustrative embodiments of the invention are shown in the accompanying drawing, throughout the several views of which corresponding reference characters are used to designate corresponding parts, and in which:

Figure 1 is a view in longitudinal section of one embodiment of the invention;

Fig. 2 is a view in vertical, transverse section, taken along the line 2—2 of Fig. 1;

Figs. 3 and 4 are comparative views illustrative of the steps of sealing off the conducting column 40 of the device in Fig. 1;

Fig. 5 is a view in elevation, partly in section, of a modified embodiment of the invention; and

Fig. 6 is a schematic diagram showing an illustrative application of the device.

As is pointed out in substantial detail in the above identified patents, the features of the present invention are attained primarily by utilizing the property of certain current conducting substances, of which metallic mercury is an example, 50 to change the physical condition or state thereof, when subjected to heat, temporarily to another physical state in which it is either non-conductive or offers a relatively high resistance to current flow. With such a substance, and knowing in advance the average current values to be nor-

mally encountered by the device, the substance may be arranged to impart a substantially fixed resistance to current flow of such value that the heat energy derived thereby will cause the conversion of a minute but sufficient quantity of such substance to its relatively non-conductive state, thereby either entirely interrupting or causing a decided decrease in the value of the current flow. The interruption or decrease in the current flow entirely interrupts or materially decreases conduction of heat energy, thereby enabling all or part of the substance which has changed its physical state to revert to its original state, which reversion again initiates or increases the current flow. The current through the device thus pulsates between maximum and minimum values, each increase in current flow producing the above vaporization, and each decrease in current flow resulting in the partial or entire re-condensation of the substance to its original state.

Referring particularly to Figs. 1 and 2, the device, which is designated as a whole as 10, comprises generally a column constituted by axially aligned members 12, 14, and 16, each whereof is pierced so as to define a bore throughout its length. The end portions of the bore are designated 18 and the intermediate portion, which extends through the intermediate section 16, is designated 18a.

Within the broader aspects of the invention, and dependent upon operating requirements, the bore sections 18 may be somewhat larger, or somewhat smaller in diameter than the bore portion 18a, which relative dimensioning appears to control in some degree at least the operating characteristics of the device. The preferred relationship is one wherein the diameters of the bore portions 18 and 18a are substantially the same, and this relationship is shown in the drawing. The sections 12 and 14 are preferably formed of conducting material, and are adapted, by means of clamps or other suitable means 20, for connection at their ends to terminals 22 of an associated electric circuit. The intermediate section 16 is preferably formed of non-conducting material. The abutting surfaces of the members 12, 14, and 16 are preferably relatively accurately formed, so that when pressed together, an exceedingly tight seal is formed therebetween, it being noted that if desired, suitable cement may be interposed between the abutting surfaces, so as to perfect the seal. An enclosing envelope 24 preferably surrounds the device and is, of course, necessarily formed of insulating material. The sections 12, 14 and 16 are retained in rigidly assembled relation to each other, in the illustrated embodiment, by clamping them between end plates 26 and 28, which are apertured to pass the sections 12 and 14, respectively, and which abut shoulders 30, 32 formed on these sections. The end plates 26 and 28 are interconnected by one or more rods 34. It will be understood, of course, that the end plates 26 and 28 may be either formed of insulating material or may be otherwise insulated from the sections 12 and 14, so that the only conducting path through the device, is directly through the sections 12 and 14 and through the material filling the bore portions 18 and 18a.

As previously stated in the general description given above, the bore portions 18 and 18a are preferably filled with a material having the property of changing its state from that of a relatively good conductor to one which is a relatively poor conductor upon the application of

heat. Mercury or mercury amalgam have been found very suitable for this purpose, it being noted that an amalgam formed by adding fifteen-tenths per cent by weight of cadmium to metallic mercury considerably increases the power output and efficiency of the device. Other elements such as tellurium, gold, silver and the like may also be used. It will be understood that in the claims, the terms mercury or metallic mercury are used as being generic to mercury and to mercury amalgam.

In the manufacturer of the device, sections 12, 14, and 16 are, of course, accurately aligned with each other and thereafter, following the application of the enclosing envelope 24, are secured in position between the end plates 26 and 28. Thereafter, after carefully cleaning the bore 18, it is preferably completely filled with the mercury. Following the filling operation, the ends of the sections 12 and 14 are sealed off in the manner clearly indicated in Fig. 1. This sealing may, of course, be effected in various ways. A preferred method of accomplishing it comprises initially forming the section such as 12 with an undercut area 36. Following the introduction of the mercury into the bore 18, a blunt edged cutting tool may be applied at the undercut area 36, thus separating the extreme end portions 12a from the main body of the section 12 and also completely closing the ends of the bore 18.

Various materials may, of course, be employed in the manufacture of the device. In practice, the insulating sections 16 may be formed of glass, plastics, ceramic, quartz or any other durable insulating material which is non-porous, and which is adapted to withstand the relatively high operating temperatures which are encountered in the operation of the device. Similarly, the end sections 12 and 14 may be formed of any suitable conducting materials, steel having been found entirely satisfactory in practice.

Before proceeding with a further statement of the structural features of the above device, its operation may briefly be described as follows. It will be appreciated that the device 10 may be variously applied to electric circuits, one illustrative arrangement being shown in Fig. 6, wherein the device 10, in parallel with a condenser 40, is connected in series with a battery 42 and the primary winding 44 of a suitable transformer T, the secondary winding 46 whereof may be used to supply any suitable load such as the lamp L. A control switch 48 is preferably inserted in the circuit, to control starting and stopping of the device. Upon closure of the control switch 48, the battery 42, of course, becomes effective to apply a voltage across the terminals 20 of the device 10, which voltage causes a current to traverse the circuit. The current flowing through the sections 12 and 14 of the device 10, of course, flows in part through the bodies of these sections and in part through the mercury within the associated parts of the bore portions 18 thereof. By virtue of the relatively great cross-sectional area of the metallic body of each section 12 and 14, as compared to the cross-sectional area of the mercury contained in the associated bore parts, a substantial majority of the current flows through the sections 12 and 14. The proportioning of the parts is preferably such that the current traversing the mercury within the bore portions 18 is insufficient to raise its temperature to the va-

porizing point. The mercury in such bore portions thus remains in the liquid phase.

On the other hand, all current traversing the device passes through the mercury in the bore 18a of the insulating section 16. As set forth above, and as also described in the above identified patents, the proportioning of the parts is such that the passage of the just mentioned current through the short bore section 18a heats the mercury therein sufficiently to cause all or part thereof to pass into the vapor phase in which it presents substantially greater resistance to the flow of the current than when in the liquid phase. This resistance to the flow of the current decreases the value of the current flowing through the device, thereby lessening the heating action, and enabling all or part of the thus vaporized mercury to re-condense into the liquid phase. This re-condensation sharply reduces the resistance to current flow through the device, resulting in a sufficient increase in such current flow to again produce the vaporization. It will be seen, accordingly, that all or part of the mercury contained within the short bore section 18a rapidly and recurrently passes between the vapor and liquid phase; and the current flowing in the associated circuit rapidly thus pulsates between maximum and minimum values, which pulsating current is reflected as an alternating current in the circuit associated with the secondary winding 48. In the claims, the sharply increased current is referred to as the normal current and the terms re-condensation or re-conversion are used to refer generically to either the partial or entire re-conversions or re-condensations which follow the abrupt decreases in current flow.

The frequency, applied voltage, reactance of the associated circuit, lengths of the bore sections 18, length of the intermediate bore section 18a, and the pressures acting upon the mercury within the bore sections appear definitely related to each other, and variations in each of these factors appear to be accompanied by variations in one or more of the others.

Considering the above factors in more detail, it will be noticed that the provision of the relatively short bore section 18a introduces several important advantages. First, since the mercury within the short section 18a is the only part of the mercury thread which is subjected to sufficient current to vaporize it, all vaporizing and re-condensing cycles occur within such relatively short section. This section is, in general, proportioned so that the length thereof is approximately equal to the length of the vapor bubble which under given pressure conditions is produced during each heating phase. Thus, the vapor bubble is definitely controlled as to position and appears correspondingly definitely controlled as to magnitude. Again, since the current through the device in large part traverses the relatively low resistance bodies of the sections 12 and 14, and encounters a high resistance only when passing through the mercury in the short bore section 18a, it will be appreciated that the power losses in the device are correspondingly minimized and its overall efficiency is increased.

The pressure acting at opposite sides of the intermediate bore section 18a, which may be termed a loading pressure, appears to be a very significant factor in the performance of the device. As is pointed out in the above Patents Nos. 2,163,708 and 2,163,709, the vaporization of

5 a part of the mercury thread develops a relatively high gas pressure at the point of vaporization, and it is desirable to so arrange the device so as to prevent this vapor pressure from forming an unduly large vapor bubble. The re-condensing action of the vapor reduces the vapor pressure thus developed tending to permit the two broken ends of the mercury thread to again come together reestablishing the maximum conductivity. It is found, however, that the re-condensing action is materially improved, and made more uniform, if a substantial pressure is applied to the vapor, and this substantial pressure also is of material assistance in controlling the initial size of the bubble.

10 In accordance with the present invention, it is preferred to apply pressures at the opposite sides of the vapor bubble which are substantially in excess of the pressures specifically utilized in the constructions described in the above Patents Nos. 2,163,708 and 2,163,709. The substantially greater pressures preferably utilized in the practice of the present invention increase the operating temperatures of the unit, since, as 15 will be understood, an increase in pressure increases the temperature point at which vaporization of the liquid mercury occurs. These increased operating temperatures can, however, be readily taken care of by suitably selecting the 20 materials from which the device is constructed and the materials suggested hereinabove have proved adequate. In the present instance, the relatively high end pressures or loading pressures acting against the vapor bubble are produced in 25 part by providing the relatively long loading column sections 12 and 14, and in part by completely filling these sections with the liquid mercury. 30 One component of the loading pressures results from the physical impedance to flow of the mercury along the relatively long bore sections 18. Another component of the loading pressure is provided by substantially completely confining the mercury thread within the sections 18 and 35 18a. It is noted that the size of the vapor bubble 40 which appears to be produced is only a very small percentage of the volume of the mercury contained in the two sections 18. The displacement of the liquid mercury required by the formation of the vapor bubble appears to be absorbed in 45 part by an actual compression of the mercury itself and in part by a minute resilient yielding of the confining metal sections 12 and 14. Independently of any specific explanation of the 50 particular manner in which the displaced mercury is absorbed in the system, it is noted that 55 the above construction produces pressures acting on the vapor bubble which appear to very materially improve its operating characteristics.

60 The applied voltage, of course, directly affects the performance of the device, since an increase in applied voltage increases the current values passed through it, and consequently, alters the time required to bring the thread to the vaporizing temperature. The reactance of the circuit 65 appears to materially control the performance of the device, particularly in respect to the tendency for an arc to form across the vapor bubble, and also in respect to the time interval required for current values in the circuit to rise and fall between the maximum and minimum 70 values.

75 With the foregoing general considerations in view, it is noted that in actual practice, devices arranged to be supplied by a six-volt source and to supply power for operating ten to fifteen foot

neon signs through a simple transformer circuit, have been found to operate satisfactorily, utilizing bore sections 18 and 18a approximately .005 of an inch in diameter; utilizing a bore section 18a approximately .045 of an inch in length; and utilizing loading sections 18 each approximately 1.25 inches in length.

In the modified embodiment of the invention shown in Fig. 5, the device is made up of conducting members 50 and 52 positioned in end-to-end relation and separated by an insulating member 54. As in the first instance, the column thus produced is provided with an axially extending bore 56, the length and diameter whereof is proportioned in accordance with the discussion given above. In this instance, the outer ends of the conducting sections 50 and 52 are of tapered form as indicated at 58, and the conducting sections are provided with complementary members 60 and 62, respectively, which are telescoped over the ends thereof. The members 60 and 62 are counterbored so as to provide relatively large reservoirs such as 64. The outer ends of the end sections 60 and 62 are closed as in the previous embodiment and are arranged to accommodate a terminal such as 66 and 68, by which the device may be connected into the circuit in the relation shown, for example, in Figure 6. The end sections 50 and 52 are provided with shoulders such as 50a, against which the inner ends of the end sections 60 and 62 abut. The latter members in turn are provided with shoulders such as 60a, which receive end plates 68 and 70, which are retained in assembled relation by studs 72. It is preferred, in charging the device with mercury, to introduce sufficient thereof into the bore 56 so as to completely fill both the end reservoirs such as 64. In some cases, the filling operation may leave a minute bubble of gas or air within the reservoirs. It is noted, however, that the virtue of the tapered formation of the ends of conducting sections 50 and 52, the extreme ends of the bore 56 are spaced from the area which such bubbles would occupy in any position of the device. Such bubbles are, therefore, effectively prevented from entering the bore 56, in accordance with the disclosures of the above identified patents.

In the broader aspects of the invention, the structure shown in Fig. 5 distinguishes from the construction shown in Fig. 1 primarily in that the column of conducting material, instead of being of entirely uniform diameter throughout its complete length, comprises a mid-section of uniform diameter, and terminates in enlarged reservoirs.

The enlarged reservoirs, as pointed out above, are preferably substantially entirely filled with mercury during the filling operation, so that the space represented by the bore through the column and by the end reservoirs constitutes a substantially solid body of mercury. It is found in practice nevertheless that the enlarged reservoirs have a cushioning effect and in a generic sense, such reservoirs perform the function of providing slightly yieldable pressure applying means.

With this relation, it will be appreciated that a device having the same dimensioning as specified above with reference to the device of Fig. 1, but also embodying the reservoirs, functions at slightly lower temperatures than the device of Fig. 1, and also has somewhat different output characteristics.

In the embodiment of Fig. 5, the entire device, with the exception of the projecting terminal parts, is encased in a body 74, which may be

composed of a suitable ceramic material. The casing 74 serves not only to protect the column structure and assist in perfecting the seal between the abutting surfaces of the members 50, 52, and 54, but also serves to improve the heat radiating characteristics of the device, thereby better enabling it to withstand the relatively high operating temperatures which may be experienced in service. It will be understood that a casing such as 74 may be utilized in connection with the structure of Fig. 1 either in conjunction with or as a substitute for the envelope 24.

It will be appreciated that the foregoing invention provides an extremely simple, economically manufactured, and reliable device for rapidly and recurrently increasing and decreasing current flow in a circuit and that although only two specific embodiments of the invention have been disclosed, various further modifications in the form, number, and arrangement of parts may be made without departing from the spirit and scope of the invention.

What is claimed is:

1. In a device for rapidly and recurrently increasing and decreasing current flow in an electric circuit, the combination of means defining a passageway, material filling said passageway having the property of being a relatively good conductor at one temperature and of changing its physical state when heated to a higher temperature to one in which it is a relatively poor conductor of current, said passageway being dimensioned so that the normal value of current flowing through the material therein produces sufficient heat energy to cause said change in physical state of a portion of said material, said means being so constructed and arranged to localize said change in state to a said portion of said material located at a substantially fixed point between the ends of said passageway.

2. In a device for rapidly and recurrently increasing and decreasing current flow in an electric circuit, the combination of means defining a passageway, material filling said passageway having the property of being a relatively good conductor at one temperature and of changing its physical state when heated to a higher temperature to one in which it is a relatively poor conductor of current, said passageway being dimensioned so that the normal value of current flowing through the material therein produces sufficient heat energy to cause said change in physical state of a portion of said material, said means being so constructed and arranged to localize said change in state to a said portion of said material located at a substantially fixed point intermediate the ends of the passageway.

3. In a device for rapidly and recurrently increasing and decreasing current flow in an electric circuit, the combination of means defining a passageway, material filling said passageway having the property of being a relatively good conductor at one temperature and of changing its physical state when heated to a higher temperature to one in which it is a relatively poor conductor of current, said passageway being dimensioned so that the normal value of current flowing through the material therein produces sufficient heat energy to cause said change in physical state of a portion of said material, means enclosing the ends of said passageway so as to define an enclosed space for said material, and said material being introduced in sufficient

quantities to substantially completely fill said space.

4. In a device for rapidly and recurrently increasing and decreasing current flow in an electrical circuit, the combination of means defining a passageway, material filling said passageway having the property of being a relatively good conductor at one temperature and of changing its physical state when heated to a higher temperature to one in which it is a relatively poor conductor of current, said passageway being dimensioned so that the normal value of current flowing through the material therein produces sufficient heat energy to cause said change in physical state of a portion of said material, means enclosing the ends of said passageway so as to define an enclosed space for said material, and said material being introduced in sufficient quantities to substantially completely fill said space, said enclosing means being formed to provide resilient cushioning reservoirs at the ends of said passageway.

5. In a device for rapidly and recurrently increasing and decreasing current flow in an electrical circuit, the combination of means defining a bore, fluid material filling said bore and having the property of being a good conductor when in a fluid state and a poor conductor when in a gaseous state, said bore being dimensioned so that the normal value of current flowing through the material therein causes the production of heat energy sufficient to change a part of said material from its fluid to its gaseous state whereby to reduce the flow of current through said material, said means being constructed and arranged to localize said change to said gaseous state to a portion of said material located at a substantially fixed point in said passageway.

6. In a device for rapidly and recurrently increasing and decreasing current flow in an electrical circuit, the combination of means defining a bore, fluid material filling said bore and having the property of being a good conductor when in a fluid state and a poor conductor when in a gaseous state, said bore being dimensioned so that the normal value of current flowing through the material therein causes the production of heat energy sufficient to change a part of said material from its fluid to its gaseous state whereby to reduce the flow of current through said material, said means being connected to an electrical circuit in such relation and being so constructed as to localize said change to a gaseous state to a portion of said material located at substantially a fixed point in said bore.

7. In a device for rapidly and recurrently increasing and decreasing current flow in an electrical circuit, the combination of means defining a bore, fluid material filling said bore and having the property of being a good conductor when in a fluid state and a poor conductor when in a gaseous state, said bore being dimensioned so that the normal value of current flowing through the material therein causes the production of heat energy sufficient to change a part of said material from its fluid to its gaseous state whereby to reduce the flow of current through said material, means enclosing the ends of said bore so as to define an enclosed space, and said material being introduced in sufficient quantity to completely fill said space.

8. In a device for rapidly and recurrently increasing and decreasing current flow in an electrical circuit, the combination of means defining a bore, fluid material filling said bore and

having the property of being a good conductor when in a fluid state and a poor conductor when in a gaseous state, said bore being dimensioned so that the normal value of current flowing through the material therein causes the production of heat energy sufficient to change a part of said material from its fluid to its gaseous state whereby to reduce the flow of current through said material, means enclosing the ends of said bore so as to define an enclosed space, and said material being introduced in sufficient quantity to completely fill said space, said enclosing means formed to provide cushioning reservoirs at the ends of said bore.

9. In a device for rapidly and recurrently increasing and decreasing current flow in an electrical circuit, the combination of means defining a bore, said means having an intermediate insulating part and conducting end parts, said bore extending through said parts and being of substantially uniform diameter throughout its length, material filling said bore and having the property of being a relatively good conductor at one temperature and having the property of changing its state upon the application of heat to a state in which it is a relatively poor conductor, said bore being dimensioned so that the normal value of current passed through said device causes said change of state, the ends of said means being connected in an electrical circuit so as to pass current through said material.

10. In a device for rapidly and recurrently increasing and decreasing current flow in an electrical circuit, the combination of means defining a bore, said means having an intermediate insulating part and conducting end parts, said bore extending through said parts and being of substantially uniform diameter throughout its length, material filling said bore and having the property of being a relatively good conductor at one temperature and having the properties of changing its state upon the application of heat to a state in which it is a relatively poor conductor, said bore being dimensioned so that the normal value of current passed through said device causes said change of state, the ends of said means being connected in an electrical circuit so as to pass current through said material, and means enclosing the ends of said bore, said material being introduced in sufficient quantity to completely fill said bore.

11. In a device for rapidly and recurrently increasing and decreasing current flow in an electrical circuit, the combination of means defining a bore, said means having an intermediate insulating part and conducting end parts, said bore extending through said parts and being of substantially uniform diameter throughout its length, material filling said bore and having the property of being a relatively good conductor at one temperature and having the properties of changing its state upon the application of heat to a state in which it is a relatively poor conductor, said bore being dimensioned so that the normal value of current passed through said device causes said change of state, the ends of said means being connected in an electrical circuit so as to pass current through said material, and means enclosing the ends of said bore, said material being introduced in sufficient quantity to completely fill said bore, and means for applying loading pressures to the material in said bore so as to cause said re-condensation of said material.

12. In a device for rapidly and recurrently increasing and decreasing current flow in an electric circuit, the combination of means defining a passageway, material filling said passageway having the property of being a relatively good conductor at one temperature and of changing its physical state when heated to a higher temperature to one in which it is a relatively poor conductor of current, said passageway being dimensioned so that the normal value of current flowing through the material therein produces sufficient heat energy to cause said change in physical state of a portion of said material, said means being so constructed and arranged that said change of state occurs at a substantially fixed point between the ends of said passageway, and means for applying loading pressures to the material in said passageway so as to cause at least partial reconversion of said portion of said material to its original state.

13. In a device for rapidly and recurrently increasing and decreasing current flow in an electrical circuit, the combination of means defining a bore, fluid material filling said bore and having the property of being a good conductor when in a fluid state and a poor conductor when in a gaseous state, said bore being dimensioned so that the normal value of current flowing through the material therein causes the production of heat energy sufficient to change a part of said material from its fluid to its gaseous state whereby to reduce the flow of current through said material, said means being so constructed and arranged that said change to said gaseous state occurs at a substantially fixed point in said passageway, and means for applying loading pressures to the material in said bore so as to cause at least a partial reconversion of said part of said material to said fluid state.
